DESIGN FOR A COMBINED TEA STEAINER AND CONTAINER

Marie J. Best, Yonkers, N. Y.

Application March 31, 1942, Serial No. 106,409

Term of patent 14 years

To all whom it may concern:

Be it known that I, Marie J. Best, a citizen of the United States, residing in Yonkers, in the county of Westchester and State of New York, have invented a new, original, and ornamental Design for a Combined Tea Strainer and Container, of which the following is a specification, reference being had to the drawings, forming a part thereof.

In the drawings:

Fig. 1 is a top plan view of a combined tea strainer and container, showing my design;

Fig. 2 is a side elevational view;

Fig. 3 is a perspective view; and

Fig. 4 is a bottom plan view thereof.

I claim:

The ornamental design for a combined tea strainer and container, substantially as shown.

MARIE J. BEST.
